(57) **CLAIM**

The ornamental design for a residential module, as shown and described.

DESCRIPTION

The patent or application file contains at least one drawing executed in color. Copies of this patent or patent application publication with color drawing(s) will be provided by the Office upon request and payment of the necessary fee.

2. Residential module

FIG. 2.1 is a front perspective view of a residential module showing my new design;

FIG. 2.2 is a rear perspective view thereof;

FIG. 2.3 is a front view thereof;

FIG. 2.4 is a back view thereof;

FIG. 2.5 is a right-side view thereof;

FIG. 2.6 is a left-side view thereof; and

FIG. 2.7 is a top view thereof.

The design solutions represent accommodation modules which are in the form of a rectangular parallelepiped; all models are characterized by an open terrace on the front facade and the glazed window and door on the front facade.

1 Claim, 7 Drawing Sheets
